METAL CONTAINER

Greeley Baker, Chicago, Ill., assignor to Continental Can Company, Inc., New York, N. Y., a corporation of New York

Application February 20, 1935, Serial No. 7,443

1 Claim. (Cl. 220—27)

The invention relates to new and useful improvements in a metal container of the friction closure type, and more particularly to a container wherein a frangible sealing member is used in conjunction with the friction closure.

An object of the invention is to provide a container of the above type wherein a frangible sealing member is disposed beneath the friction closure and secured to the can top by shaping of the metal thereof to provide a clamping means for the sealing member.

A further object of the invention is to provide a container of the above type wherein the can top is bent upwardly to form a shoulder and thence laterally and back upon itself to form a pocket for the purpose of receiving the edge of the sealing member and clamping the same to the can top.

These and other objects will in part be obvious and will in part be hereinafter more fully disclosed.

Referring to the drawing:

Fig. 1 is a view partly in side elevation and partly in vertical section showing the container embodying the improvements of the invention.

Fig. 2 is an enlarged partial vertical sectional view of the container showing the friction closure and frangible sealing member in place.

Fig. 3 is an enlarged vertical sectional view similar to Fig. 2 but showing a slightly modified form of a friction closure.

The invention relates particularly to metal containers of the friction closure type having a frangible sealing member used in conjunction therewith. The container comprises a body portion preferably of metal having ends double seamed thereto, one of said ends being in the form of a container top having a central opening and a vertical friction wall surrounding said opening. A friction closure is provided for the container, said closure being adapted to frictionally engage the vertical friction wall of the container top for closing the container. A frangible sealing member or disc is used in conjunction with the friction closure. The disc is disposed so as to extend across the opening surrounded by the vertical friction wall and underlie the friction closure with the peripheral edge portion thereof contacting with the container top between the vertical friction wall and the double seam. The container top has a portion of the metal thereof bent upwardly to form a rounded shoulder and thence laterally and back upon itself to form a pocket for receiving the peripheral edge portion of the sealing disc. This pocket is

also adapted to receive a sealing material in which said peripheral edge portion of the sealing disc is adapted to be embodied. A portion of the metal which forms the bottom wall of the pocket is also bent downwardly and upwardly again to form a clamping member for clamping a frangible sealing disc against the upper face of the pocket. In this manner the sealing disc extends across the opening in the container top, is secured at its peripheral edge by the clamping member, and becomes imbedded in the sealing material to establish a hermetic seal for the container.

Referring more in detail to the drawing:

A container embodying the invention is indicated at 4. The container is preferably of metal 15 comprising a body portion 5 having a bottom end 6 double seamed thereto as indicated at 7, and a top end 8 secured thereto by a double seam 9. The top end 8, or can top as it is usually called, has a central opening with an upstanding vertical friction wall 10 surrounding said opening. The vertical friction wall terminates at its upper end in a hollow strengthening bead 11. A friction closure 12 is provided for the container having a depending vertical friction wall 13 which is 25 adapted to frictionally engage the friction wall 10 of the can top for closing the container. The friction closure 12 is provided with an outwardly turned laterally extending hollow bead 14 at its upper end which is adapted to overlie the can 30 top.

A frangible sealing member or disc 15 is used in conjunction with the friction closure 12 for further sealing the container. This frangible sealing disc is preferably made of aluminum, but 35 might be made of any other frangible material, such as tagger's tin, paper or the like. The disc 15 is of such diameter as to be adapted to extend across and beyond the opening defined by the vertical friction wall, underlie the friction closure, 40 and have the peripheral edge portion 16 thereof contact with the under face 17 of the can top between the vertical friction wall and the double seam of the container. The container top has a portion of the metal thereof adjacent the central opening therein bent upwardly to form a rounded shoulder 18 and thence laterally and back upon itself to form a pocket 19. Said pocket 45 19 is adapted to receive a sealing material 20 and the peripheral edge portion 16 of the sealing disc 50 is imbedded therein. The portion of the metal forming the bottom wall 21 of the pocket is also bent downwardly and upwardly to form a clamping surface 22 for clamping the peripheral edge portion 16 of the sealing disc against the under 55

clamping surface 17 of the can top. When the frangible sealing member is clamped in place and the peripheral edge thereof imbedded in the sealing material, a hermetic seal is established for the container.

In the form of the invention shown in Fig. 3 of the drawing, a slightly modified friction closure 12 is provided. The friction closure in this modified form is what is termed as an outside 10 slip closure and is adapted to frictionally engage the outer face of the vertical friction wall 10 of the can top. The friction closure above described comprises a depending friction wall 23 which terminates at its lower edge in a hollow strengthening bead 24, the upper end thereof being bent outwardly in the form of the laterally extending bead 25 which may be grasped by the hand for removing said closure.

In manufacture, containers of the type disclosed by the invention are assembled at the factory. The frangible sealing member is clamped to the can top, the friction closure is inserted, and the can top is double seamed to the container body. In this manner the containers are shipped 25 to the packer who fills through and closes the opposite end of the container by double seaming a conventional end thereto.

When it is desired to open a container of the type disclosed by the invention, the friction closure 30 is first removed and the frangible disc cut away by a knife or other sharp instrument.

From the above it will be apparent that a container has been devised wherein a hermetic seal has been provided for a container of the friction 35 closure type and wherein the removal of the frangible disc used in conjunction with the friction closure would readily indicate that the contents of the container have been tampered with. It is to be further noted that the closure member,

frictionally engaging the upstanding wall of the can top 10, serves to maintain the clamping surfaces 17, 22 in tight contact with the peripheral edge portion of the sealing disc 15.

It is obvious that minor changes in the details of construction and the arrangement of parts may be made without departing from the spirit of the invention as set forth in the appended claim.

Having thus described the invention, what I claim as new and desire to secure by Letters Patent, is:—

A metal container comprising a body portion having a can top secured thereto by seaming, said can top having a depending portion adjacent the body wall of the container and an inwardly extending portion terminating in a vertical upstanding wall substantially co-extensive with the depending portion and surrounding a central opening, the inwardly extending portion of the can top between the depending portion and the upstanding wall being bent to provide a rounded shoulder at the lower end of the said upstanding wall, a pocket for a sealing material between the shoulder and the depending portion and cooperating clamping surfaces at the opening into said pocket; a frangible sealing disc extending across the central opening in the can top and contacting with the said rounded shoulder and extending between the clamping surfaces and into said pocket, the said clamping surfaces contacting with the sealing disc for holding the same imbedded in the sealing material and against the rounded shoulder for forming a tight seal between the disc and the can top, and a closure member adapted to frictionally contact with the said upstanding wall for closing the container and for maintaining the clamping surfaces in contact with the sealing disc.

GREENLEY BAKER.
